UNITED STATES PATENT OFFICE.

THOMAS I. A. TOMASINI, OF SAN FRANCISCO, CALIFORNIA.

SPRING-CLIP.

1,114,312.

Specification of Letters Patent.

Patented Oct. 20, 1914.

Application filed November 21, 1913. Serial No. 802,292.

To all whom it may concern:

Be it known that I, THOMAS I. A. TOMASINI, a citizen of the United States, and a resident of the city and county of San Francisco and State of California, have made certain new and useful Improvements in Spring-Clips, of which the following is a specification.

This invention relates to springs, and 10 more particularly to spring clips.

One of the principal objects of the invention is to provide an auxiliary spring or spring clip to be attached to a leaf spring for keeping the leaves in place, and to augment the resiliency of the leaf spring.

Another object of the invention is to provide an auxiliary spring of the class described which will be simple in construction, strong and durable, efficient in operation and 20 inexpensive to manufacture.

With these and other objects in view, which will become apparent as the description proceeds, the invention resides in the construction, combination and arrangement 25 of parts hereinafter more fully described and claimed, and illustrated in the accompanying drawing in which like characters of reference indicate like parts throughout the figures, of which—

30 Figure 1 represents a side elevational view of one end of a leaf spring, showing the invention as applied thereto, Fig. 2 represents a top elevational view of a leaf spring showing the invention in place thereon. Fig. 3 35 represents a vertical transverse sectional view taken on the plane indicated by the broken line 3—3 of Fig. 1.

Referring more particularly to the drawing, the outer end of the second leaf 5 of an 40 ordinary leaf spring is enlarged, and is provided with a transverse bore through which extends a bolt 6 for securing in place a substantially inverted U-shaped clip 7, which comprises a central rounded portion 8 overhanging the top leaf 7' of the spring in spaced relation thereto, and downwardly 45 bent arms 9 extending in parallel relation to each other and at right angles to portion 8, and which have their lower ends flattened 50 and enlarged as at 10 and provided with

openings through which bolt 6 extends, whereby the clip is secured in place on leaf 5, the bolt being headed on one end and provided with a nut on the opposite end to keep the arms tight up against the leaf spring. 55 An auxiliary spring 11 is interposed between leaf 7' and clip 7, and said spring comprises a strip of spring material substantially the same width as the leaf spring, having its ends turned up as at 12, said strip 60 being bowed outwardly adjacent the upturned ends as at 13, and bowed inwardly between the out bowed portions, as at 14, the inwardly bowed portion 14 at its central point bearing against the rounded portion 65 8 of the clip, and the curvature of the inwardly bowed portion 14 which engages portion 8 of the clip, is of substantially the same curvature as portion 8 so that spring 11 will be held in place longitudinally of the 70 leaf spring, and will be prevented from slipping at its ends laterally thereover. It is evident that spring 13 will keep the spring leaves 5 and 7' in place all the time and that it will tend to prevent breaking of the 75 spring leaves, and at the same time will give, as the leaf spring gives, thereby aiding the resiliency of the leaf spring.

Although I have described the preferred embodiment of my invention, I may desire 80 to make such changes in the construction, combination and arrangement of parts thereof, as do not depart from the spirit of the invention, and the scope of the appended claim.

Having thus fully described my invention, what I claim as new and desire to secure by Letters Patent is:—

The combination with a leaf spring, of an inverted, substantially U-shaped clip connected at its ends to one of the leaves, and at its central portion overhanging a second leaf, said second portion being rounded, and a strip of spring material interposed between the second leaf and clip, said spring 90 bearing at its ends against said second leaf, and being bowed inwardly at its central portion, said inwardly bowed portion being of a curvature equal to the curvature of the rounded portion of the clip, and engaging 95 100

said rounded portion, said strip on each side of the inwardly bowed portion being bowed outwardly from the center of the strip to the second leaf engaging parts, whereby the strain on said strip is distributed, said outwardly bowed portions at their highest points being positioned at a greater distance relative to said second leaf than the overhanging portion of the clip.

THOMAS I. A. TOMASINI.
